UNITED STATES PATENT OFFICE.

CHARLES H. BUCKELEW, OF PLAINFIELD, NEW JERSEY.

SUBMARINE TUNNEL.

SPECIFICATION forming part of Letters Patent No. 349,301, dated September 21, 1886.

Application filed March 16, 1886. Serial No. 195,380. (No model.)

To all whom it may concern:

Be it known that I, CHARLES H. BUCKELEW, of Plainfield, in the county of Union and State of New Jersey, have invented an Improvement in Submarine Tunnels, of which the following is a specification.

This invention relates to a metallic tunnel built in sections upon the shore, and when completed temporary bulk-heads are placed in the ends to make the sections water-tight. These sections are of the proper size and shape, and each is provided with one or more vertical shafts of sufficient length to reach above the water when the tunnel has been sunk, and the sections are launched and floated to place and sunk, and then bolted together; or they may be bolted together and then sunk. After one section has been properly bolted to the adjacent section, the bulk-head is removed to open one section into the next. The tunnel is weighted to sink it, and it is also protected by ballast filled into cribs or tanks that are provided for its reception along outside the tunnel.

In the drawings, Figure 1 is a cross-section of the tunnel completed. Fig. 2 is a plan view of a portion of one of the sections, and Fig. 3 is a section, in larger size, of the interlocking and connecting parts of the adjacent ends.

The tunnel is shown as adapted to two tracks, and of a rectangular shape in section; but my improvements are available with tunnels of any desired size or sectional shape. The external ribs, 11, are of iron or steel, with flanges, to which the plates 22 are riveted. These plates are of iron or steel, and the bottom bars, 3, and ribs or angle-irons 4 are added for obtaining the desired strength. Where the tunnel is used for two tracks, it is preferable to introduce a range of columns or a central partition at 5 to support the roof. The sections are of suitable length, and are similar to a boiler or a tubular bridge so far as described, the joints of the plates being caulked. Upon the top of each section there is a vertical shaft, 8, of boiler-iron. The same is removably bolted to the top of the section, and the same is of a size to admit workmen to descend to the tunnel-section. After the tunnel is completed, the entrance to the shaft at the top of the tunnel is to be closed by a plate bolted to

place, and then the shaft is unbolted and removed.

One of the special features of my invention relates to the manner of constructing the ends of the sections so that they can be bolted to each other. Upon the ends of each section are inwardly-projecting rims 11, and these rims are perforated for the passage of connecting-bolts, and the rim 11 on one section, A, corresponds to the rim on the other section, B, so that the bolt-holes 13 are in line with each other all around the rim of the section. The portion of the rim in which the holes 13 are made is covered on the outside with a sheet of rubber, 16, or other yielding material, and the same is secured in place by cement, or, preferably, by screws 17, the faces of the rims being recessed where such screws are received, and the portion of the rim through which the holes 13 pass preferably projects beyond the rest of the rim, as shown, so that when the two sections are set together the rubber or yielding coverings will come tightly against each other; and to guide the sections into place, and to facilitate the placing of one section of the tunnel properly against the previously-placed section, I make use of the lapping plates 15, riveted upon the top angles of one section, and resting upon the top of the next section when the parts are in place. As an additional convenience for facilitating the placing of the end of one section against the end of the other section, I provide glasses in frames attached to the bulk-heads, as at 19, the glasses coinciding in position with each other, so that it can be observed when the sections are in their proper relative positions.

In order to permanently connect the sections together after they have been properly placed, I drive the pointed bolts 20 through the holes 13, and in so doing pierce the india-rubber or other yielding material, and this is done without admitting water to any considerable extent, and by screwing up the nuts 21, the sections are firmly connected together. These bolts are to be at suitable distances apart and of a size proportioned to the strength required. These rims 11 might be fastened directly to the plates 22 of the tunnel; but I prefer to make the same as parts of the shells 12, which shells are in sections and bolted to

gether by internal flanges, and provided with the flanges 10, by which they are bolted or riveted to the tunnel-plates 2. By making use of these shells I am able to obtain the necessary width for the connecting-rims 11 without diminishing the internal diameter of the tunnel. The removable bulk-heads 22 are secured by the top bolts, 23, that pass into the rims, and by removing these top bolts the bulk-heads can be taken away, so that the tunnel-sections are opened into each other. It will be evident that these removable bulk-heads can be used in other sections as the work progresses. Rods of lead 15 or of sheet metal rolled up are preferably inserted into the channels 26 around the faces of the rims. These form a permanent packing as they are compressed, and the rubber packing is protected from the action of the water. The shells forming the joint-shells at the ends of the sections can be filled in flush with cement after the tunnel has been otherwise completed.

To sink the tunnel-sections I provide upon 25 the outer sides of the tunnel bins or ballast-tanks, into which ballast or concrete is to be introduced. These ballast-tanks are made of cast or wrought iron, the ribs at the bottom of the tunnel being extended beyond the plates 30 for receiving the bottom plates, 31, of the bins, and these ballast-tanks extending up to the top of the tunnel, or nearly so, and there are connected to the external ribs or angle-irons of the tunnel by the plates or straps at 34. 35 These ballast-tanks open at the top ends, and are to be filled with ballast or concrete, and it is preferable to cover the top of the tunnel with cement or concrete to the desired depth for protecting the iron.

40 By my improvement very little work has to be done by workmen in a diving-bell, and confined air under pressure in the tunnel while constructing the same is rendered unnecessary, because the bed of the river only 45 requires to be dredged to the proper depth at the line of the tunnel, so that the proper depth of water will exist in the channel over the tunnel, and the mud and sand will fill in around the tunnel after it has been sunk.

50 If desired, the sections of the tunnel may be bolted together after being floated to place and before they are weighted and sunk, and as the sections are screwed up tightly they will be brought into their proper relative positions.

I claim as my invention—

1. In submarine tunnels, the method herein specified of excluding water and uniting the sections, consisting in preparing the sections with rims extending inwardly and perforating them with holes that correspond in the section ends that are to come together, covering such holes with india-rubber or similar material to exclude the water, placing the sections end to end with the rubber coverings against each other and the holes coinciding, 65 and simultaneously perforating the rubber and connecting the sections by driving bolts through the holes, substantially as set forth.

2. The tunnel-sections made of iron plates and ribs, in combination with the inwardly-projecting rims at the ends perforated for the connecting-bolts, the shells or enlargements connecting the rims to the tunnel-sections, the removable bulk-heads attached to the rims, and the lapping plates attached to one section and resting upon the other section, the packing between the sections, and the pointed attaching-bolts passing through the rims and through the packing, and the nuts for the bolts, substantially as set forth.

3. The tunnel-sections made of iron plates and ribs of the proper size and strength, bottom ribs extending beyond the vertical sides of the tunnel, in combination with the bins and partitions upon the sides of the tunnel for 85 the reception of ballast, substantially as specified.

4. The combination, with the tunnel-sections and the removable bulk-heads, of rims extending inwardly, and to which the removable bulk-heads are connected, and bolts for fastening the sections together, and the packing of lead or other soft metal introduced into a groove at the outer surface of the rim, substantially as set forth.

5. The combination, with the wrought-metal tunnel-sections, of ranges of hollow cast-iron shells bolted together and attached to the tunnel-sections, and having inward rims perforated for the reception of the connecting-bolts, 100 and the removable bulk-heads attached to such rims, substantially as set forth.

Signed by me this 10th day of March, A. D. 1886.

CHAS. H. BUCKELOW.
